(57) **CLAIM**

The ornamental design for a drain rack, as shown and described.

DESCRIPTION

FIG. 1 is a front, left and top perspective view of a drain rack showing my new design;

FIG. 2 is a rear, right and bottom perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof; and,

FIG. 9 is a front, left and top perspective view of the drain rack of FIG. 1, shown in condition of use.

The broken lines showing a drain rack are for the purposes of illustrating environment and forms no part of the claimed design.
